Inventor
John W. Burtt

United States Patent Office.

BAXTER C. SWAN, OF PHILADELPHIA, PENNSYLVANIA.

Design No. 4,608, dated January 24, 1871.

DESIGN FOR BOXES FOR THE TOPS OF BUREAUS.

The Schedule referred to in these Letters Patent and making part of the same.

To all whom it may concern:

Be it known that I, BAXTER C. SWAN, of the city and county of Philadelphia, in the State of Pennsylvania, have invented a new and original Design for Boxes for the Tops of Bureaus; and I do hereby declare the following to be a specification thereof, reference being had to the accompanying drawing, in which—

Figure 1 is a central longitudinal section, and

Figure 2 a plan view of a box made according to my design.

The box is of the kind usually secured to the tops

of bureaus for the support of the standards in which the glass is hung.

The front of the box is formed on an ogee, A, intersected, as shown, by the outwardly-concave curves B B, which form its sides.

What I claim as my invention, and desire to secure by Letters Patent of the United States, is—

The design for a box for the tops of bureaus, as shown and described.
